UNITED STATES PATENT OFFICE.

RUDOLPH C. RUTZKE, OF ST. LOUIS, MISSOURI.

LIQUID-LEVEL INDICATOR.

Application filed October 6, 1922. Serial No. 592,726.

The object of this invention is to provide a simple, cheap, and efficient oil level indicator for the crank-case of internal-combustion engines that employs the splash system 5 of lubrication.

This device can, also, be utilized in other locations.

It is more particularly adapted for the Ford, Chevrolet, and similar kinds of motor 10 cars and for motor cars having oil gages with two cocks.

In the accompanying drawings forming part of this specification, in which like numbers of reference denote like parts wherever they occur.

Figure 1 is a side elevation of the improved liquid level indicator.

Figure 2 is a vertical sectional view of the same.

20 The device is attached by a threaded elbow or coupling 1 to the opening at the bottom of the crank-case (not shown) from which the crank-case is customarily drained, the outer arm 2 of the elbow 1 being in threaded connection with the pipe 3, leading to the elbow 4, which is in threaded connection with the said pipe 3, and, also, with pipe 5.

A nipple 6 extending from the bottom of 30 cup 7, containing chamber 8, is adapted to be moved in either direction on the thread 9 on pipe 5 and to be locked in any position thereon by lock-nut 10.

Screw plug 11 closes an opening in elbow 35 2, but is removed therefrom when it is desired to drain the crank-case.

A cap 12 for cup 7 is internally provided with shoulder 13, which rests on the upper edge 14 of cup 7, flange 15 depending below 40 shoulder 13 and closely engaging the outer part of the side wall of cup 7.

Pipe 16 is externally threaded, so as to co-operate with threads within nipple 17, borne by cap 12, so that cap 12 and cup 7 45 are vertically adjustable on pipe 16 the same as on pipe 5, this adjustability being for the purpose of allowing latitude for different makes of machines or variations at different times in the same machine. A lock-nut 18 above nipple 17 co-operates with lock-nut 10 below nipple 6, the two conjointly holding the cup 7 stationary after it has been accurately adjusted to the particular machine to which it is attached.

55 The pipe or hollow rod 16 passes through a hole in the fixed or relatively stationary

part 19 of the hood or any other suitable comparatively immovable part of the machine, and after all adjustments have been made the pipe 16 is locked in position relative to the said member 19 by the lower lock nut 20 and the upper lock-nut 21. By the means of attachment herein described, namely, the passage of pipe 16 through member 19, the use of lock-nuts 20 and 21, 60 and the screw-threaded attachments of elbow 1 to the crank-case, this device is so attached to the machine as not to rattle and to be absolutely secure.

A gage-rod 22, having a head 23, is adapted to slide lengthwise through pipe 16 and through an opening in cap 24, preferably screw-threadedly attached to the upper end of pipe 16.

70 A float 25 is borne by the lower end of rod 22, the lower extremity of which rod 22 is preferably screw-threaded, so that threaded washers or nuts 26 and 27 will hold float 25 upon rod 22. A tit or tits 28 upon the floor of cup 7 and a tit or tits 29 projecting within cap 12 prevent float 25 from binding either upon the floor of cup 7 or against cap 12, allowing the movement of the oil indicated by the oil-level line 30 readily to move float 25 in either direction, according to the 80 height of the oil-level 30.

75 A small hole is pierced through flange 15 and through the upper part of the wall of cup 7 and permits the passage therethrough of the pin 31 having the head 32, which pin 31 fastens cap 12 to cup 7. A threaded bushing 33 is inserted in an opening out of cap 12 or at a suitable place in cup 7, and provides a vent for any surplus oil. Too much oil in the crank-case results in its being 90 forced into the cylinders, where it fouls them and from which it makes its way to the spark-plugs, besides which it causes a smoking engine and other bad results. With this device attached to an engine it acts as an 100 oil equalizer as well as an oil gage and indicator, because whenever there is any excess oil in the crank-case it automatically makes its escape through the vent provided by the bushing 33.

105 The eye of the operator will take note of the height of the head 23, which is carried up or down by the floating higher or lower of float 25, the elevation or lowering of which depends upon the height of the oil-level 30. The oil level 30 depends upon the oil-level within the crank-case to which this 110

device is attached, on the principle that a liquid always seeks its own level, and the oil-level within cup 7 is necessarily the same as the oil-level within the crank-case.

This device is so arranged that even when the oil-level 30 is at its lowest, as approximately shown in Figure 2, there remains enough oil in the crank-case to allow the engine to run a considerable length of time thereafter without burning the bearings of the crankshaft.

When the float 25 is higher in cup 7 than is shown in Figure 2 the head 23 indicates that there is more oil in the crank-case, and by watching the height of head 23 above cap 24 the operator notes with accuracy approximately how much longer the engine can be run without danger to the bearings and without the addition of oil in the crank-case.

It is well known that one of the greatest sources of injury to internal-combustion engines, particularly those used in motor vehicles, motor boats, aeroplanes, and the like, is the burning out of crankshaft bearings, for which there can be neither reason or excuse when this device is used, as it operates easily, automatically, and with certainty and precision.

Having thus described this invention, I hereby reserve the benefit of all changes in form, arrangement, order, or use of parts, as it is evident that many minor changes may be made therein without departing from the spirit of this invention or the scope of the following claim.

I claim:

A liquid level indicator comprising an oil cup having a central opening in the bottom thereof and an external nipple extending from the bottom thereof in line with the central opening in the bottom of the cup, said nipple being internally threaded; a cap for said cup having a central opening in its top and an internal shoulder adapted to rest on the upper edge of the cup and a flange depending below the shoulder and closely engaging the side wall of the cup; a nipple formed integral with the said cap and extending upwardly from the top of the cap in line with the central opening therein, said nipple being internally threaded; an oil-feed pipe in threaded connection with the nipple of the said cup; a tube threaded externally for the greater portion of its length and having the lower end of its threaded portion in threaded connection with the nipple of the said cap; a float in the oil cup; a stem carried by the float and extending upwardly through the said tube; said tube and said oil-feed pipe being normally fixed and stationary relative to one another and the said cup and cap being adjustable thereon; and a removable locking pin engaged in aligned openings in the flange of the cap and the upper part of the wall of the cup and serving to fasten the said cap to the said cup.

In testimony whereof I hereunto affix my signature.

RUDOLPH C. RUTZKE.
